W. H. WOOD.

ORTHOPEDIC APPLIANCE FOR FOOT TREATMENT.

APPLICATION FILED DEC. 16, 1916.

1,240,286.

Patented Sept. 18, 1917.

UNITED STATES PATENT OFFICE.

WILLIAM H. WOOD, OF CLEVELAND, OHIO, ASSIGNOR TO STANLEY W. COOK,
TRUSTEE, OF CHICAGO, ILLINOIS.

ORTHOPEDIC APPLIANCE FOR FOOT TREATMENT.

1,240,286.

Specification of Letters Patent. Patented Sept. 18, 1917.

Application filed December 16, 1916. Serial No. 137,322.

To all whom it may concern:

Be it known that I, WILLIAM H. WOOD, a citizen of the United States, residing at Cleveland, in the county of Cuyahoga and State of Ohio, have invented certain new and useful Improvements in Orthopedic Appliances for Foot Treatment, of which the following is a specification.

My invention relates to improvements in appliances for foot treatment, and has for its general object to provide an appliance for remedying both a bunion or outward displacement of the first metatarso-phalangeal articulation and a falling of the transverse arch of the foot due to downward displacement of the heads of one or more of the middle metatarsal bones.

A particular object of my invention is to provide a neat, effective and comfortable means for attaching the article to the foot and insuring the positioning of its principal members in accurately-adjusted positions.

In the drawings wherein I have illustrated an embodiment of my invention—

Figure 1 is a side elevation of an appliance showing its position in use.

Fig. 2 is a longitudinal section on line 2—2 of Fig. 1; and

Fig. 3 is a transverse section on line 3—3 of Fig. 1.

In the practice of my invention I combine with a toe splint arranged to extend along the outside of the foot from a point in rear of, to a point in front of, the first metatarsal phalangeal articulation; anchorage means comprising a stall for the great toe and a foot-encircling band or belt, respectively connected with the front and rear end of the splint; and a "hump-element" adapted to exert a restorative upward pressure upon the under side of the foot adjacent the heads of certain metatarsal bones, said hump-element associated with the belt in advantageous relation.

In the specific construction shown the toe splint structure 10 comprises a metallic spring body 11 having a convexo-concave bunion-receiving pocket 12, preferably apertured ovally at its crest, as shown at 13, and integrally connected with front and rear extensions or arms 14 and 15. To the inner side of this splint is connected a felt padding 16, preferably somewhat larger in all dimensions than the splint. In the broader aspect of my invention, however, any splint-

structure for spanning the first metatarso-phalangeal joint will serve. A toe encircling band 17, preferably adapted to be laced, as at 18, is connected to the front arm of the splint to form a stall for the great toe by 19 which the front arm of the appliance may be securely anchored. Specifically the band is stitched at 19 to the felt pad.

20 indicates a hump element, associated with, and having its position generally controlled by adjustment of a belt 21 that encircles the foot just back of the ball thereof. This hump is preferably integral with an under-foot spring 22 shaped to follow the transverse curvature of the foot and run up 25 the side thereof, as shown in Fig. 3, for pivotal connection, at 23, to the splint arm 15. The hump proper 24 is of convexo-concave section and of circular or other appropriate plan contour, so that when forced against 30 the under side of the foot just in rear of the heads of the metatarsal bones, it will exert a restorative upward pressure upon said bones if the latter be misplaced or dropped. The foot encircling belt or strap 21 is adapted 35 to be buckled snugly around the foot and is arranged to have its buckle ensconced within the underside concave of the hump plate. Specifically belt 21 has an anchored tab portion 26, secured to the splint arm 15 structure, preferably by anchorage of one extremity of said belt-tab to the pivoting rivet 23, the opposite extremity of said section passing through one of two diametrically opposed slots 25 and 25' in the hump plate 40 45 and carrying a buckle 27 within the confines of the under side of the hump plate. The other or adjustable section 28, of the belt, is adapted to have its "loose" end passed through the other hump plate slot and engaged with the buckle 27, and its other end is adjustably engageable with the splint. Thus the "fast" end of this belt-section is attached to a wire loop 30 having a hook 31 that may engage any one of notches 32 made 50 in the splint-arm 15. By moving the belt-hook 31 fore or aft relatively to the splint arm, thereby directing the belt in different lines of traverse of the foot, the fore-and-aft position of the hump may be varied, the 55 pivotal connection 23 of the underfoot spring permitting this hump-movement.

For greater comfort of the wearer the hump may be overlain by a fabric or leather cover-piece 33 slotted as at 35, 35' in register 60

with hump-plate slots 25, 25', so as to be held in place by the belt.

While I have herein described in some detail a particular embodiment of my invention for purposes of full disclosure of one operative form thereof, it will be understood by those skilled in the art that many changes may be made in the structure without departure from the spirit of my invention within the scope of the appended claims.

Having described my invention, what I claim is:—

1. The combination of a relatively rigid structure adapted to extend along a side portion of the foot, means to attach one end thereof to the foot, a belt to attach the other end thereof to the foot with the belt passing in rear of the metatarsal heads, said belt having one end fast to the rigid structure and its other end adjustably connectible with said rigid structure at different longitudinal points to throw the course of the belt that passes beneath the foot into different lines of traverse, and a hump element coacting with the belt to be positioned with respect to the length of the foot by the stated adjustment of the belt.

2. The combination of a toe-splint, a belt connected at one end to the rear end of the splint and at its other end adjustably con-

nectible to different points near the rear end of the splint, and a hump member engaged by the under-foot course of said belt.

3. The combination of a toe-splint, a belt connected to the rear end of said toe-splint, said belt having a fastening device located in its under-foot course, and a convexo-concave hump element engaging said belt and enveloping the fastening in its concave.

4. The combination of a toe-splint, a belt having its one end fixed thereto and its other end adjustable lengthwise thereof, and a down-and-under curved under-foot plate pivoted to said splint, having a metatarsal hump portion slotted to receive the belt, said belt having a fastening means within the concave underside of said hump.

5. The combination of a belt; a fastening device for the ends of the belt; a hump plate carried by said belt, and overlying the fastening device and a cover for said hump-plate.

6. The combination of a belt; a hump plate carried by said belt, and a cover for said hump-plate, said hump-plate and cover having registering openings through which the belt is threaded.

In testimony whereof I hereunto set my hand.

WILLIAM H. WOOD.
